LOUIS W. GATES, OF NEW HAVEN, CONNECTICUT, ASSIGNOR TO C. COWLES & COMPANY, OF NEW HAVEN, CONNECTICUT, A CORPORATION OF CONNECTICUT.

LOCKING HANDLE.

1,424,245.

Specification of Letters Patent. Patented Aug. 1, 1922.

Application filed December 27, 1921. Serial No. 524,822.

To all whom it may concern:

Be it known that I, LOUIS W. GATES, a citizen of the United States, residing at New Haven, county of New Haven, State of Connecticut, have invented an Improvement in Locking Handles, of which the following is a specification.

This invention relates to vehicle door locks, especially to the means for securing the lock operating spindle in the door, and to means operable at will for locking the spindle against turning movement.

It is an object of the invention to provide a lock operating spindle with an escutcheon plate which may be adjusted to different angles with respect to the spindle, so that the spindle may be mounted in the door or lock in a horizontal position, with the escutcheon fitting snugly against the surface of the door, even though this surface may be curved or inclined at an angle to the axis of the spindle, to provide means for preventing turning movement of the spindle bearing in the escutcheon while allowing this angular adjustment, and to provide means operable at will to lock the spindle against turning movement in the bearing to prevent unlatching of the door.

With these and other objects in view I have devised the simple structure disclosed in the accompanying drawing, in which—

Fig. 1 is a side elevation of a lock operating handle and spindle with the escutcheon mounted thereon, portions thereof being broken away to better illustrate the construction.

Fig. 1^A is an end view of the handle.

Fig. 2 is a partial, sectional view of the escutcheon plate and the spindle bearing.

Fig. 3 is a rear view of the escutcheon.

Fig. 4 is a side elevation of the bearing with a portion thereof broken away.

Fig. 5 is an end elevation of the bearing.

Fig. 6 is an end elevation of the retaining means.

Fig. 7 is a side elevation thereof with a portion broken away, and

Fig. 8 shows two side views of the locking bolt.

The escutcheon 10, as is usual in this type of lock, is adapted to be secured to a surface of a door, indicated in dotted lines at 11, by any suitable means, such as screws, not

shown, extending through openings 12 in the escutcheon. The escutcheon illustrated is 55 pressed from a piece of sheet metal, although it may, if preferred, be made of a casting, and is provided with an outwardly projecting flange 13 having an interior spherical surface, in which is seated a bearing 14 having an exterior spherical surface 15 adapted to seat in the first mentioned spherical surface within the flange, this bearing being retained therein by means of a retaining ring 16 secured to the escutcheon by any suitable means, such as solder 17. The bearing is provided with a longitudinal extending cylindrical opening 18 providing a bearing for the lock spindle 19, and allows turning movement of this spindle therein. To prevent the bearing rotating in the escutcheon, it is provided with a longitudinally extending slot 20, and a pin 21 is riveted to the escutcheon and has a free end projecting into said slot. For best results, this pin 7 should project into the slot substantially at the mid length of the bearing when this bearing is so positioned that the axis of the spindle is substantially perpendicular to the escutcheon, as shown in Fig. 2, as this construction and arrangement will allow the bearing to rock with respect to the escutcheon in all directions, giving a universal angular adjustment, but at the same time will prevent turning movement of the bearing in the escutcheon. By turning or rotating movement of the bearing in the escutcheon, as mentioned throughout the specification and claims, I mean the rotation of the bearing substantially in the plane of the escutcheon about the longitudinal axis of the spindle.

The bearing 14 is also provided with one or more openings or recesses 22, preferably arranged substantially central and extending radially thereof, and arranged substantially 90° from each other and from the slot 20, as shown in Figs. 4 and 5. Mounted to slide in a transverse opening 23 in the spindle is a bolt 24 adapted to have one end thereof slid into either one of the openings 22, this bolt being of a length substantially equal to the diameter of the spindle so that it may be drawn wholly within the confines of said spindle. It is provided with a transverse channel 25 adapted to receive an eccentric pin 26 mounted on the end of a lock cylinder 27

secured to turn in the spindle by any suitable means, such as a pin 28 lying partly in the body of the spindle and partly in an annular groove 29 in the cylinder 27. This 5 lock cylinder may be of any suitable construction provided with any suitable key operated means for preventing turning thereof when the handle is locked, as is well known, the end of the handle 30 being provided with a suitable key slot 31 for the insertion of a key to rotate this cylinder, and through the eccentric pin 26 to slide the bolt 24 into one of the openings or recess 22 to lock the spindle against turning within the 10 bearing, or to withdraw it therefrom to unlock the spindle. It will be apparent that, when this bolt is extended into an opening 22, the handle is locked against turning movement because the bearing 14 is prevented from rotating within the escutcheon by the pin 21. The two openings 22 being arranged at right angles to each other, allow the positioning of the escutcheon on the face of the door either vertically or horizontally. 15

The bearing on the spindle in the bearing 14 is provided by a reduced portion 32 which provides a stop shoulder 33 coacting with the outer end of the bearing 14 to limit the 20 inward movement of this spindle in the bearing. Withdrawal of the spindle may be prevented by any suitable means, such as a collar 34 bearing against the inner end of the bearing 14, and secured to the spindle 25 by any suitable means, such as solder 35.

It will be apparent from the foregoing description that when the spindle and the escutcheon are applied to a door, the spindle may be mounted with its axis extending 30 horizontally but the escutcheon may be set at different angles to lie flush with the surface of the door. Also, in addition to the advantages obtained from such an arrangement, the spindle may be locked against 40 turning movement within the escutcheon. It will be apparent that the device is very simple in construction and, therefore, may be easily manufactured and assembled, and is not likely to be easily gotten out of order in 45 use.

Having thus set forth the nature of my invention, what I claim is:

1. In combination, an escutcheon having an opening therethrough, a bearing mounted 55 in said opening for angular adjustment relative to said escutcheon, means for preventing rotation of the bearing in the escutcheon, a lock spindle mounted to turn in said bearing, and means for locking the 60 spindle to said bearing.

2. In combination, an escutcheon, a bearing mounted for angular adjustment relative to said escutcheon, a lock spindle mounted to turn in said bearing, and means for locking 65 the spindle to said bearing.

3. In combination, an escutcheon adapted to be secured to a door, a lock spindle mounted for angular adjustment in said escutcheon and also for turning movement therein, and means for locking the spindle 70 to the escutcheon.

4. In combination, an escutcheon having a substantially spherical recess, a bearing having a substantially spherical surface in said recess and adapted for angular adjustment therein, means for preventing rotation of the bearing in the escutcheon, a lock spindle mounted to turn in the bearing, and means for locking said spindle to said bearing. 75

5. In combination, an escutcheon, a bearing having universal adjustment in said escutcheon, a lock spindle mounted to turn in said bearing, and means for locking the spindle against said turning movement. 80

6. In combination, an escutcheon having a substantially spherical recess therein, a bearing member having a substantially spherical surface fitting in said recess, a ring contacting the spherical surface of the bearing member 90 to retain the same in said recess, means for securing the ring to the escutcheon, means for preventing rotation of the bearing in the escutcheon, a lock spindle mounted to turn in said bearing, and means for locking the 95 spindle to the bearing.

7. In combination, an escutcheon, a bearing mounted for angular adjustment only relative to said escutcheon and provided with a recess, a lock spindle mounted to turn in 100 said bearing, a bolt carried by the spindle and mounted for sliding movement transversely thereof, and means for moving an end of said bolt into said recess to lock the spindle to the bearing. 105

8. In combination, an escutcheon, a bearing mounted for angular adjustment relative to said escutcheon, means to prevent rotation of the bearing in the escutcheon comprising a slot extending longitudinally of the bearing and a pin carried by the escutcheon and extending into said slot, a lock spindle mounted for turning movement in said bearing, and means for locking the spindle to the bearing to prevent said turning movement. 110

9. In combination an escutcheon having a substantially spherical recess, a bearing having a substantially spherical surface in said recess and adapted for angular adjustment 120 therein, means for preventing turning movement of the bearing in the escutcheon comprising a slot in the bearing extending longitudinally thereof and a pin carried by the escutcheon and extending into said slot, a lock spindle mounted for turning movement in said bearing, and means carried by the spindle and movable to engagement with the bearing to lock the spindle against said turning movement. 125

10. In combination an escutcheon having a substantially spherical recess, a bearing having a substantially spherical surface in said recess, means for preventing turning movement of the bearing in the recess while allowing angular adjustment relative to the escutcheon, a lock spindle mounted to turn in said bearing, said bearing being also provided with an opening, a transversely sliding bolt carried by the spindle, and means 10 for moving the bolt into engagement with said opening to lock the spindle.

In testimony whereof I affix my signature.
LOUIS W. GATES.
